UNITED STATES PATENT OFFICE

99,918

DESIGN FOR A LUCKY CAMPAIGN COIN

Edwin A. Halsey, Lynchburg, Va.

Application May 8, 1936, Serial No. 62,558

Term of patent 7 years

To all whom it may concern:

Be it known that I, Edwin A. Halsey, a citizen of the United States, resident of Lynchburg, in the county of Campbell and State of Virginia, have invented a new, original, and ornamental Design for a Lucky Campaign Coin, of which the following is a specification, reference being had to the accompanying drawing, forming part thereof.

Fig. 1 is a view of the obverse, and
Fig. 2 of the reverse of the lucky campaign coin showing my new design.

I claim:
The ornamental design for a lucky campaign
coin, as shown.

EDWIN A. HALSEY.
